UNITED STATES PATENT OFFICE.

CARL A. PALMGREN, OF SOUTH CHICAGO, ILLINOIS, ASSIGNOR TO STEEL ART TOOL COMPANY, OF CHICAGO, ILLINOIS, A CORPORATION OF ILLINOIS.

DOG.

1,158,832.

Specification of Letters Patent.

Patented Nov. 2, 1915.

Application filed January 11, 1915. Serial No. 1,572.

To all whom it may concern:

Be it known that I, CARL A. PALMGREN, a citizen of the United States, residing at South Chicago, in the county of Cook and State of Illinois, have invented a new and useful Improvement in Dogs, of which the following is a specification.

My invention relates to certain new and useful improvements in dogs, and is fully described and explained in the specification and shown in the accompanying drawings, in which:

Figure 1 is a rear elevation of my improved dog; Fig. 2 is a side elevation, looking from the right in Fig. 1; Fig. 3 is a section on the line 3 of Fig. 1; Fig. 4 is an elevation of one of the jaws, looking from the right in Fig. 3; Fig. 5 is, in the main, an elevation looking from the left in Fig. 3, but with the rear plate removed, the upper portion of the figure being a central transverse section, and Fig. 6 is an elevation of the rear plate, looking from the right of Fig. 3, the cam ring being shown superposed thereover in dotted lines.

Referring to the drawings, 7 is the rear plate of my dog. It is circular in contour, plain on its rear surface and centrally perforated at 8. Surrounding the perforation 30 is a plurality of projections 9, extending forward from the front face of the rear plate. These projections have their peripheral surfaces perpendicular to the plane of the rear plate and their front surfaces parallel to said plane, each projection being thus, in geometrical terms, a prism. The faces of the projections are, roughly speaking, sector-shaped, the exact form being shown in the drawings and are spaced apart 35 so as to form between them radial parallel-walled guide-ways 10. In these guide-ways lie jaws 11, each having teeth 12 at its inner end and a beveled part 13 at its outer end. The outer end of each dog is provided with 40 a lip 14 at the extremity of which is a forwardly extending hooked flange 15.

An operating ring 16 lies in front of the rear plate. The forward face of this ring is plain, its outer surface is provided with 50 gear teeth 17 cut to coöperate with a worm, and the inner surface of the ring is provided with notches forming cam surfaces 18 equal in number to the jaws and so arranged that the rotation of the ring in a counter-clockwise direction, as viewed in Fig. 5, will force

the jaws inward in an obvious manner. For the purpose of withdrawing the jaws, the rear face of the ring is cut away to receive the lip 14 and grooved at 19 to receive the flanged hook on the lip 14 of the jaws. The 60 grooves 19 are parallel to the cam surfaces 18, whereby a clockwise direction of the ring, as viewed in Fig. 5, will withdraw the jaws.

20 is the front plate of the dog, plain on its front side and centrally perforated at 21. It is provided at its outer periphery with a deep flange 22, the main portion of which is of the thickness of the jaws, the operating ring and the projections 9 on the rear plate, plus a working clearance. The outer part of the flange 22 is provided with a further extension or shoulder 23 of the thickness of the rear plate. There is thus formed a completely closed annular structure, the front 70 and outer periphery of which is formed by a front plate and its flange and the rear and inner periphery of which is formed by the rear plate and its projections 9, the spaces between the projections being filled 75 by the jaws 11.

For the purpose of turning the operating ring, a tangential hole 24 is drilled through the flange of the front plate 22 so as to intersect the inner periphery of said flange. 85 In the hole 24 is rotatably mounted a worm 25 keyed against longitudinal movement. The ends of the worm are provided with squared openings 26 which can be engaged by a wrench, and the entire worm is well within the hole made to receive it so that there are no projecting parts. For purposes of assembling the structure, the rear outer edge of the operating ring is cut down to the plane of the gear teeth, as shown at 27 90 in Fig. 5.

In order to prevent rotation of the dog with reference to the back plate, there are provided two rearwardly projecting tapered pins 28 which are preferably oval in cross-section and which enter the structure so as to lie partly in the front and partly in the rear plate, as shown.

The operation of the structure will be very readily apparent from the description of its construction, the jaws can be locked on any piece of work in a perfectly obvious manner and the dog will perform the usual functions of such devices. The structure is advantageous because it is cylindrical in form offer- 105 110

ing no projecting parts upon which the operator can be injured, and because it automatically centers itself with reference to the work, and applies its force to the work in a 5 symmetrical manner.

In driving with my dog the arrangement should be such that the driving force applied to the casing is in the direction that will tend to rotate the operating ring with 10 reference to the jaws, which are retarded by the work, so as to tighten the jaws. There is necessarily a certain lost-motion between the worm and the worm gear teeth on the operating ring. It is found in practice 15 that the operation, when the dog is driven in the proper direction, is to rotate the operating ring to the extent of this lost-motion and tighten the jaws.

I realize that considerable variation is possible in the details of the construction herein shown, and I do not intend to limit myself thereto, except as pointed out in the following claim, in which it is my intention to claim all the novelty inherent in the device

as broadly as is permitted by the state of the 25 art.

What I claim as new and desire to secure by Letters Patent is:

A dog comprising a disk-shaped hollow casing having a smooth cylindrical periphery and a through central aperture, a face plate interfitting therein, radially guided jaws within said casing movable toward and from said aperture, an operating ring within said casing having cams engaging said jaws to 30 advance and retract them, a single means within said casing operable from without 35 for moving said ring to adjust said jaws equally and simultaneously, and holding pins locking said casing and face plate together. 40

In testimony whereof I have hereunto set my hand this 5th day of January, 1915.

CARL A. PALMGREN.
